UNITED STATES PATENT OFFICE.

JOHN L. GARLINGTON, OF SNAPPING SHOALS, GEORGIA.

IMPROVEMENT IN FIRE-PLACES.

Specification forming part of Letters Patent No. **140,621**, dated July 8, 1873; application filed April 19, 1873.

To all whom it may concern:

Be it known that I, JOHN L. GARLINGTON, of Snapping Shoals, in the county of Newton and State of Georgia, have invented a new and Improved Grate for Fire-Places, &c., of which the following is a specification:

In the accompanying drawing, Figure 1 represents a front view of my improved grate, and Fig. 2 a vertical transverse section of the same on the line *c c*, Fig. 1.

Similar letters of reference indicate corresponding parts.

The object of my invention is to construct an improved grate, which may be adjusted to any chimney-place, allowing full control of the fire and increasing the heating properties of the same. My invention consists of a grate with inclined back plate and sliding dampers to throw forward the heat and regulate the same. It also consists in adjustable side plates to fit the grate into a chimney.

In the drawing, *A* represents the grate, of suitable metal, adapted in shape and size to the open fire-places in use. It consists of upright side plates *B*, which may be made of sheet or cast iron with extension plates *C* at top and bottom to adjust the grate to the height of the fire-places. The extension-plates have short vertical slots *a*, which, in connection with rivets or set-screws *b*, lock them to the side plates *B*. The top extension-plates *C* carry the laterally-connecting plate *d*, to which the face or front plate *e* is attached. Plate *d* and guide projections *f*, at the sides of the top extension-plates *C*, have a slight upward inclination and carry the damper *D*. The back plate *E* is applied laterally to the extending sides *B*, and riveted or otherwise connected to them. This back plate *E* and damper *D* may also be secured to the brick sides of the chimney-plates in case no side plates *B* are used. Back plate *E* is inclined under an angle of about forty-five degrees toward the front, throwing thereby the heat into the room instead of allowing the same to escape to the chimney. A

large proportion of the heat lost in common fire-places may thereby be utilized and the expense of open fires be considerably reduced. Projecting strips *g* are cast or riveted on back plate *E* in an upward direction to prevent the wood or logs from packing too closely toward the back, permitting at the same time the continuous admission of oxygen to the fire from all sides. The upper end of back plate *E* has a flange, *h*, turned up under a right angle, which corresponds with several projecting strips *h'* of back-extension plate *F*, allowing the forward or backward adjustment of the same, and controlling thereby the draft to the chimney and the degree of heat. Extension-plate *F* is guided in suitable manner by rods *i* on the back plate *E*, and connects by its chimney-plate *K* bent up under a right angle to the chimney. The smoke passes up between damper *D* and plate *K* to the chimney, and both together regulate the fire at will. Coal or wood may be burned in this grate, the former in a suitable basket the other with the common andirons. The back plate *E* rests on the brick wall of the fire-plate, which should not be too high, so as to permit convenient arrangements of the different parts.

Having thus described my invention, I claim as new and desire to secure by Letters Patent—

1. The back extension-plate *F* with lateral strips *h'*, guide-rods *i*, and chimney-plate *K*, as described.
2. The top and bottom extension-plates *C* having slots *a*, in connection with damper *D* and side plates *B*, substantially as described.
3. The combination of the extension-plate *F*, lateral strips *h'*, guide-rods *i*, plate *K*, plates *C* having slots *a*, side plates *B*, and damper *D*, as shown and described.

JOHN L. GARLINGTON.
